UNITED STATES PATENT OFFICE.

HARRY W. SMITH, OF WORCESTER, MASSACHUSETTS.

DESIGN FOR WOVEN FABRIC.

SPECIFICATION forming part of Design No. 29,753, dated November 29, 1898.

Application filed October 7, 1898. Serial No. 692,953. Term of patent 14 years.

To all whom it may concern:

Be it known that I, HARRY W. SMITH, a citizen of the United States, residing at Worcester, in the county of Worcester and Commonwealth of Massachusetts, have invented and produced a new and original Design for Woven Fabrics, of which the following is a specification.

The accompanying drawing is a face view 10 of a portion of the fabric.

The design consists of a series of woof members 1, arranged in pairs across the face of the fabric with an intermediate lighter member 2, thus forming alternate spaces 3 3 of 15 equal width and intermediate spaces 4 4 of greater width, the latter containing a plurality of woof-threads. The warp members 5 5 are arranged in groups of four, and each is composed of a plurality of threads, and all

are separated from each other by spaces narrower than the spaces between the several groups. As the warp members traverse the larger of the spaces 4 4 the threads composing the two inner of the four members are distributed so as to produce with the woof- 25 threads the effect of a substantially rectangular closely-woven figure, which is one of the distinguishing features of the design.

What I claim is—

The design for a woven fabric as herein 30 shown and described.

In testimony whereof I have hereunto set my hand in presence of two subscribing witnesses.

HARRY W. SMITH.
